UNITED STATES PATENT OFFICE.

WILLIAM GLEDHILL, OF BLACKBURN, ENGLAND.

LOOM.

Application filed December 26, 1922. Serial No. 309,065.

To all whom it may concern:

Be it known that I, WILLIAM GLEDHILL, a subject of the King of Great Britain and Ireland, residing at Blackburn, England, have invented certain new and useful Improvements in Looms, of which the following is a specification.

This invention relates to a loom weighting motion; and it consists in the novel construction and combination of the parts hereinafter fully described and claimed whereby the normal tension of the warp threads is released at intervals, and is allowed to come on again, as required.

In order that the said invention may be clearly understood and readily carried into effect, the same is described more fully with reference to the accompanying drawings, wherein:—

Fig. 1 is a rear view, and Fig. 2 an end view of part of a loom with the invention applied thereto, and

Fig. 3 is an end view shewing a modification.

The whip roll A is bolted to two two-armed levers a in such manner that it can be adjusted towards and away from the centres a¹ of such levers. Attached to the latter are screwed rods terminating in hooks a² for attachment to ropes or chains b which pass around the necks or ruffles b¹ of the warp beam B. When weaving light cloth, springs such as a³ may be interposed between the levers a and adjusting nuts a⁴ to take up any slackness in the chains and help the oscillatory movement of the warp beam caused by the opening and closing of the shed and at the same time to minimize the movement of the whip roll. When heavy cloth is being woven the springs a³ can be dispensed with. The lower ends of the ropes or chains b after being coiled around the necks or ruffles of the warp beam are attached to a bar C that is cranked at its ends and mounted in levers D. In the modification shewn in Figs. 1 and 2 these levers are pivoted at d and connected by links d¹ and springs d² with the front ends of the levers a. The levers D operate in conjunction with strong springs d³ which offer resistance to their upward movement and to enable the weight to be taken off the ropes, or chains b when it is required to turn the beam back, or remove it, the cranked rod C is provided with a handle c which can be turned to raise the rod and so take the ten-

sion off the ropes or chains. During the process of weaving, each time the shed is completing its opening movement after the beat up, the pull on the warp threads turns the warp beam forward thereby raising the levers D slightly and taking a certain amount of compression off the spring d². This relieves the drag on the ruffles sufficiently to prevent extra tension or strain being put upon the warp threads as the shed is continuing to open after the beat up, with the result that less breakages of warp threads occur and the output of the loom is increased. In the modification shewn in Fig. 3 the lever D is pivoted intermediately of its length and is provided at its front end with a weight d⁴ which can be adjusted to any required position along the lever.

The normal tension of the warp threads is relieved at intervals and allowed to come on again when required. In Figs. 1 and 2 this is effected by a cam E engaging a roller e on a lever e¹ that is rigidly fixed on a rock shaft e². This shaft extends across the loom and is free to turn in bearings e³. Rigidly secured to the rock shaft e² outside each loom end frame is an arm e⁴ connected by a link e⁵ to the lever D. When the loom is in motion the cam E imparts a slight oscillating motion to the lever D and such cam is so shaped and timed as to relieve the tension during the opening of the shed and restore it when the shed is closed. In the modification shewn in Fig. 3 the lever e¹ is extended to engage a roller e⁶ mounted on a bracket e⁷ that is attached to one of the sley swords F, the arrangement being such that as the sley goes back the roller e⁶ travels over an incline e⁸ on the lever e¹ and so depresses the latter thereby temporarily taking the pressure of the spring d² off the chain b.

By the invention described, when the shed is open, there is less weight on the healds and warp threads owing to the turning movement of the warp beam which is facilitated by the yielding of the springs. By mounting the whip roll on pivoted arms it yields when the pull on the warp threads is increased owing to the warp beam getting less in diameter. This yielding reduces the tension on the chains which encircle the necks or ruffles of the warp beam and consequently allow the latter to turn more freely than it would otherwise do if no such relief were granted.

What I claim as my invention and desire to secure by Letters Patent in the United States is:—

1. In a loom weighting motion, the combination, with a warp beam, flexible connections wound on the neck of the warp beam, pivoted upper and lower levers connected at one end to the respective ends of the said flexible connections, a connection between the other ends of the said upper and lower levers, a whip roll carried by the said upper levers, and springs which depress the said lower levers and stretch the warp; of means for automatically raising the said lower levers at predetermined intervals against the pressure of the said springs, thereby temporarily relieving the normal tension of the warp threads.
2. In a loom weighting motion, the com-

bination, with a warp beam, flexible connections wound on the neck of the warp beam, pivoted upper and lower levers connected at one end to the respective ends of the said flexible connections, a connection between the other ends of the said upper and lower levers, a whip roll carried by the said upper levers, and springs which depress the said lower levers and stretch the warp; of a rock-shaft, arms secured on the rock-shaft, means operatively connecting the said arms with the said lower levers, and driving devices for operating the rock-shaft at predetermined intervals, thereby raising the lower levers against the pressure of the said springs and temporarily relieving the normal tension on the warp threads.

In testimony whereof I affix my signature.
WILLIAM GLEDHILL.
